UNITED STATES PATENT OFFICE

2,581,802

HEADREST

Allan J. Lyons, Glendale, Calif.

Application September 16, 1949, Serial No. 116,185

1 Claim. (Cl. 155—174)

1

This invention relates to headrests, and more particularly to a headrest that may be substituted for an ordinary pillow or cushion.

It is among the objects of the invention to provide an improved headrest which provides full ventilation and avoids the use of feathers, or other stuffing material to which many people are allergic, which is highly flexible and extremely comfortable, is of light weight and easily portable, includes a removable cover which can be changed whenever necessary or desired, and which is simple and durable in construction, economical to manufacture, and neat and attractive in appearance.

Other objects and advantages will become apparent from a consideration of the following description and the appended claim in conjunction with the accompanying drawing, wherein:

Figure 1 is a perspective view of a headrest illustrative of the invention;

Figure 2 is a top plan view of the frame of the headrest illustrated in Figure 1;

Figure 3 is an end elevation of the frame illustrated in Figure 2;

Figure 4 is a front elevation of a somewhat modified form of headrest;

Figure 5 is a top plan view of a fragmentary portion of a still further modified form of headrest;

Figure 6 is a cross-sectional view on the line 6—6 of Figure 5.

With continued reference to the drawing, the improved headrest comprises, in general, a frame 10, a fabric band 11 detachably connected at its opposite ends to the frame at respectively-opposite ends of the latter, and a removable cover 12 surrounding the band.

The frame 10 is preferably formed of a single length of wire or rod of a resilient material, such as steel, and includes a straight, rear base member 13 extending longitudinally of the frame, legs 14 and 15 projecting upwardly from the base member 13 at the respectively-opposite ends of the latter and disposed substantially at right angles to the base member, two hairpin-shaped loops 16 and 17 extending perpendicularly from the upper ends of the legs 14 and 15, respectively, and disposed in spaced-apart, substantially-parallel relationship to each other, two secondary legs 18 and 19 extending respectively from the ends of the loops 16 and 17 joined to the legs 14 and 15 closely adjacent and substantially parallel to the legs 14 and 15, respectively, two arms 21 and 22 projecting forwardly from the lower ends of the secondary legs 18 and 19, respectively, and

2

disposed in spaced-apart, substantially-parallel relationship to each other and in spaced, substantially-parallel relationship to the respective loops 16 and 17, and a front base member 23 joining the forward ends of the arms 21 and 22 and disposed in spaced, substantially parallel relationship to the rear base member 13.

In providing the frame from a single length of wire or rod, the rear base member 13 constitutes the center portion of such length of wire or rod and the front base member 23 is provided by the two end portions of such length of wire or rod, the two ends of the wire or rod being welded together at 24 to constitute a continuous frame.

The rear and front base members 13 and 23 and the two end arms 21 and 22 constitute a rectangular base structure adapted to rest on a supporting surface, such as a bed, floor, beach or deck, and the legs 14, 15, 18 and 19 support the two band-carrying loops 16 and 17 above this base structure. Each loop comprises two closely-adjacent wire or rod portions, as indicated at 25 and 26 in Figure 3, and has a rounded outer end 27 to facilitate slipping the fabric band 11 onto the loops. Each of the legs 14 and 15 is provided with an arcuately-curved formation intermediate its length and the curved portions of these legs may be welded to the legs 18 and 19, respectively, if desired.

In the somewhat modified construction illustrated in Figure 4, the portions 26' of each of the loops 16 and 17 is provided with an outwardly-convex, curved portion, which curved portions 35 engage the respectively-opposite ends of the band 11 to more firmly secure the band onto the loops.

The band 11 is preferably provided from a length of webbing of suitable, resilient fabric, preferably having threads of rubber or other flexible, resilient material, woven therein. The two ends of the piece of webbing are secured together to provide a continuous band of double thickness and the loops 16 and 17 are received in this band at the respectively-opposite ends of the band. 45 The band is originally somewhat shorter than the distance between the two loops, so that the band will be slightly stretched and the two loops forced somewhat together in applying the band to the frame.

50 In the modified arrangement illustrated in Figures 5 and 6, the band 11' is illustrated as a single thickness of webbing having a hem 27 provided at each end and an opening 28 at the mid-length location of each hem. A hanger 29 has a straight bar portion 30 included in each hem 27 and a

hook 31 extending through the opening 28 to engage the upper member 25 of each of the loops 16 and 17. This upper member 25 is preferably provided intermediate its length with an offset portion 32 which receives the hook 31. The hook 31 is open so that it can be associated with and removed from the loop member 25 as desired, and it is to be understood that the hem 27 and hanger 29 are duplicated at the opposite end of the band 11'.

The hangers 29 greatly facilitate the attachment of the band 11' to the frame and the removal of the band from the frame for the purpose of changing the cover 12 or for other purposes as may be desired.

The cover 12 is a continuous or doubled band of suitable fabric, such as the kind of fabric from which pillow cases are ordinarily made, and is of a size to closely surround the resilient band 11, but is somewhat shorter than the band 11'.

Because of the resiliency of the frame and the flexibility of the head-supporting band 11, the band 11 provides a soft and comfortable cushion for the head and may be arranged to support the head only a slight distance above the surface upon which the base of the frame rests. The cover 12 can be changed by taking one end of the band 11 off of the associated loop 16 or 17, removing the cover already on the band and placing a new cover thereon, and then replacing the end of the band 11 on the corresponding loop.

The invention may be embodied in other specific forms without departing from the spirit or essential characteristics thereof. The present embodiments are, therefore, to be considered in all respects as illustrative and not restrictive, the scope of the invention being indicated by the appended claim rather than by the foregoing de-

scription, and all changes which come within the meaning and range of equivalency of the claim are, therefore, intended to be embraced therein.

What is claimed is:

A headrest comprising a resilient frame, and a resilient fabric band detachably connected at its opposite ends to said frame at respectively-opposite ends of the latter, said frame comprising a rectangular base portion, legs extending upwardly from each rear corner of said base portion, and closed loops projecting forwardly from said legs at respectively-opposite ends of the frame, said loops being of elongated shape and disposed in spaced-apart, substantially-parallel relationship to each other and in spaced, substantially-parallel relationship to the respectively-adjacent ends of said frame base portion, and said band comprising a piece of webbing having its ends secured together to provide a continuous band of double thickness, said band bodily receiving said frame loops at the respectively opposite ends of the band and being stretched between said loops.
